UNITED STATES PATENT OFFICE.

FRANCIS M. TINKHAM, OF SPRINGFIELD, MASSACHUSETTS.

WINDOW-SHADE EXHIBITOR.

SPECIFICATION forming part of Letters Patent No. 256,412, dated April 11, 1882.

Application filed February 7, 1882. (No model.)

To all whom it may concern:

Be it known that I, FRANCIS M. TINKHAM, a citizen of the United States, residing at Springfield, in the county of Hampden and State of Massachusetts, have invented new and useful Improvements in Window-Shade Exhibitors, of which the following is a specification.

This invention relates to the details of the construction of an improved device for use by dealers in window-shades and analogous articles, upon which may be hung in a manner convenient for rolling and unrolling them a great variety of window-shades, the object being to provide an improved device upon which the various samples and styles of said shades may be grouped together, and be so hung thereon that each one may be properly exhibited for the inspection of purchasers, or so that many shades may be at the same time exhibited, and in such a way that one shall not interfere with the other.

In the drawings forming part of this specification, Figure 1 illustrates a window-shade exhibitor constructed according to my invention, on which are shown several shades properly suspended as when in use. Fig. 2 is a like view to Fig. 1, but showing the exhibitor with no shades upon it.

In the drawings, *b* is the exhibitor-stand. *a* is the frame pivoted upon the upper end of the vertical post of said stand at *c*, Fig. 2. *d* are the window-shades.

The frame *a* of the shade-exhibitor consists of four end posts, *x x x x*, which are supported upon and by a horizontal bar, *n*, and two vertical bars, *o o*, in an outwardly-inclined position from said bar *n* upward, and two of said inclined posts *x x* having their upper ends

joined by a cross-bar, as shown, and one of 40 said posts *o* constitutes one end of said frame, the two ends being joined by two tie-rods, *v v*.

The above-described frame *a* is adapted to be turned around upon the top of the stand *b*, a pivot-bolt passing through the horizontal 45 bar *n* at *c* into said stand.

The shades *d* are hung upon ordinary shade-rollers between the inclined posts *x x* of opposite sides of the frame *a*, and upon shade-roller fixtures of the ordinary description, one 50 above the other, as shown. Thus the vertical line of each shade as it hangs down is in front of or in the rear of those above and below it, and each shade can be drawn down and rolled up without interfering with its neighbor; or 55 several shades may be unrolled for exhibition at the same time upon both sides of the frame, and the latter being rotated upon the stand *b*, all of the shades thereon are fully and conveniently shown.

In practice the top and ends of the frame *a* are covered with any suitable material, to protect the shades which are hung thereon from dust and to impart to the frame a more finished appearance.

What I claim as my invention is—

The within-described window-shade exhibitor, consisting of the frame *a*, having two outwardly-inclined shade-supporting posts, *x x*, upon opposite sides thereof, the tie-rods *v v*, 70 the horizontal bar *n*, and the stand *b*, to which said frame is pivotally attached, combined and operating substantially as set forth.

FRANCIS M. TINKHAM.
